UNITED STATES PATENT OFFICE.

CLAUDE A. P. TURNER, OF MINNEAPOLIS, MINNESOTA.

DEFORMED BAR.

1,288,763.

Specification of Letters Patent. Patented Dec. 24, 1918.

Application filed July 2, 1918. Serial No. 243,000.

To all whom it may concern:

Be it known that I, CLAUDE A. P. TURNER, a citizen of the United States, residing in the city of Minneapolis, in the county 5 of Hennepin, in the State of Minnesota, have invented certain new and useful Improvements in Deformed Bars, and have described the same in the following specification, illustrated by the accompanying drawings.

My invention relates to that class of deformed bars which are commonly used for reinforcement of concrete construction, and which are individually provided with a plurality of projections, surface irregularities, or socalled deformations, for the purpose of increasing the mechanical bond resistance operatively occurring between the bar and the concrete in which it is embedded. It is 15 the main object of the invention to facilitate the formative process of rolling a bar of this class; to avoid reducing the strength of the bar in its final pass between the rollers, and to provide the bar with all necessary or 20 desirable deformations without producing thereby any avoidable reduction of its strength; to distribute the mechanical bond resistance of the deformations uniformly around the body of the bar; at the same 25 time to adapt the completed bar to be bended, as use may require, in either or both of two planes, at right angles with each other, without any interference between the deformations and the bending rolls; and in general to produce a deformed bar of simple 30 design and easy construction, and of superior convenience and efficiency. To accomplish these objects I incorporate in my improved bar, as parts thereof, a cylindrically round 35 bar body and a plurality of spaced projecting ribs, formed integrally therewith, which have a special form, a special individual arrangement and a special distribution upon the round body.

In said drawings, illustrating the best manner in which I have contemplated applying the principles of the invention, Figure 1 is a side elevation of a specimen portion of a deformed bar which is constructed 45 in accordance with these principles. Fig. 2 is a cross-section of the same bar on the section line 2—2 of Fig. 1. Fig. 3 is a side elevation of the same portion of the same bar rotated in the direction of the arrow in 50 Fig. 2 through an angle of forty-five degrees from the position shown in that figure.

Fig. 4 is a cross-section on the section line 4—4 of Fig. 3. Fig. 5 is a partial axial section of the same bar.

In the illustrated specimen of my invention the body of the bar is a straight round rod, denoted by the numeral 6. It is of any desired or predetermined length, and is provided with a plurality of ribs, 7, 8, 9, 10, formed integrally therewith and thereon by the operation of formatively compressing the rod between rolls. Each of these ribs has in side elevation the form of a crescent, as shown in Figs. 2 and 4; and in cross section resembles a truncated screw-thread, as shown 70 in Fig. 5. These ribs are individually disposed in circumferential directions on the periphery of the bar body, and are uniformly spaced apart in four separated series extending lengthwise of the bar, and comprising the ribs 7, 8, 9 and 10 respectively. Each series forms part of a single sector of the bar, and each rib spans an arc of approximately sixty, and not more than ninety, 75 degrees of such sector; so that in an end elevation of the described bar all the ribs are seen to lie within a circumscribed square whose sides are tangent to the body 6. The ribs of each sector are spaced uniformly apart a distance preferably exceeding the 80 diameter of the bar; those of diametrically opposite sectors are directly opposite; and those of adjacent sectors are in relatively 85 staggered positions, as shown.

As the ribs are distributed uniformly 90 around the body of the bar, the bond resistance referred to is operatively distributed in the same manner; as the individual ribs lie circumferentially and not lengthwise of the bar, they are neither weakened 95 nor ruptured by longitudinal tension or compression when the bar is bent; and, as the deformations lie within said circumscribed square, the bar can be passed between bending rolls without either choking 100 the rolls or flattening out the ribs, and can be bended in either of two rectangularly intersecting planes with equal smoothness and facility.

Such being the construction and operation 105 of my improvements in deformed bars, I claim as my invention

A reinforcing bar for concrete comprising an unbroken cylindrical body portion having a plurality of metallic ribs formed integrally therewith, said ribs being of the 110 same size and shape and being small in

height and thickness, whereby the minimum of metal is subtracted from the bar and the maximum of bonding strength and ease in rolling is secured, the said ribs being arranged in four equally spaced longitudinal rows, the ribs in each row being staggered with respect to the ribs in any adjacent row and each rib being one of a pair of dia-

metrically opposite ribs, whereby the mechanical bond of the concrete to the bar will be equally distributed and the bar may be bent in two directions at right angles without interference with the ribs.

Witness my signature at Minneapolis, Minnesota, June 28th, 1918.

CLAUDE A. P. TURNER.
